[57] ABSTRACT

A composite thread rolling tool assembly comprising a hub and a removable thread forming sleeve. The sleeve has flat end surfaces permitting a plurality of sleeves to be assembled on an arbor for forming the threads thereon. The sleeve is retained on the hub by a snap ring having inclined end surfaces.

FIG. 1

FIG. 3

FIG. 2

COMPOSITE THREAD ROLL

BRIEF SUMMARY OF THE INVENTION

The thread roll disclosed herein is intended for use on a thread rolling fixture of the kind disclosed in my prior U.S. Pat. No. 3,353,390. Prior to the present invention the thread rolls were integrally formed and as finished, had about the same overall configuration as the assembly disclosed herein. This required removal of very substantial amounts of metal in machining operations, thus representing extra expense in waste of material as well as the cost of machining.

In accordance with the present invention, the thread rolling tool is formed of two independent integral separate portions. One portion is a thread rolling portion in the form of a sleeve having a thread formation in its outer surface. The sleeve has flat end surfaces so that a plurality of sleeves may be assembled on a single arbor for the production of the thread formation on the outer surfaces of the sleeves, as by milling, grinding or the like. The second portion of the tool is a hub having an end portion shaped to be received within the opening through the sleeve. The hub portion is generally cylindrical although it is provided at one end with a narrow abutment flange and intermediate its ends is provided with a plurality of grooves, preferably of V-shaped cross-section.

As a result of separation of the thread rolling tool into the two main portions, it is possible to select the material for each portion which suits the particular requirements of operation rather than selecting a material which is a compromise of these properties. Moreover, the sleeves may be produced from commercially available tubular stock from which wafers are cut and machined to provide the required configuration. The hubs may be machined from tube stock with a minimum or stock removal.

The portion of the hub which receives the sleeve is of generally cylindrical configuration except for the provision of a flat surface extending across one side. The opening through the thread rolling sleeve is of matching configuration, with a flat surface which engages the flat surface on the hub to prevent relative rotation.

The sleeve is fixed on the hub against axial movement by the provision of an abutment flange at one end of the hub and by the use of a snap ring received in an annular groove in the hub adjacent a side of the sleeve. The sleeve is thus engaged between the flange and the split ring.

Preferably, the annular grooves are of V-shaped cross-section and the split ring has a cross-sectional shape, the radially inner portion of which is of V-shaped cross-section to match the configuration of the groove. The outer portion of the ring is preferably also of V-shaped cross-section and cooperates with a similarly inclined peripheral portion at one side of the sleeve which engages the inclined portion of the ring. This provides a maximum dimension for the ring opposing shearing force developed by axial thrust on the sleeve. At the same time the inclined surfaces cause the axial thrust of the sleeve to tend to force the ring more firmly into seating engagement in the groove.

A number of grooves may be provided on each hub so as to accommodate rolls of different width. The rolls or sleeves are preferably provided with symmetrical inclined surfaces at opposite sides surrounding the open-

ing therethrough so that the rolls or sleeves may be reversed.

BRIEF DESCRIPTION OF THE DRAWINGS

FIG. 1 is an exploded perspective view of the components making up the thread rolling tool.

FIG. 2 is an enlarged end view of the tool assembly.

FIG. 3 is a section on the line 3—3, FIG. 2.

DETAILED DESCRIPTION

The thread rolling tool assembly comprises the three component parts illustrated in exploded relation in FIG. 1. These parts are the roll or sleeve supporting hub 10, the thread forming roll or sleeve 12, and the snap ring 14. The parts are assembled as shown in FIG. 2 and in use, the assembly is mounted on a cylindrical pin or free rotation thereon. For this purpose the hub 10 is provided with a cylindrical opening 16 which permits the tool assembly to rotate freely on the pin. As more fully disclosed in my prior patent 3,353,390, the thread rolling tools are adapted to be mounted in pairs in position to span a rotating work piece. In practice, the work piece may be driven in rotation by suitable mechanism such as that provided in an automatic screw machine, and the thread rolling fixture may be advanced radially to cause the opposed thread rolls to engage the rotating work piece and to move thereon to a substantially centered position. This generally tangential movement of each thread roll with reference to the work piece tends to cause rotation thereof in opposite directions. This opposed rotation is superimposed on the rotation occasioned by solid engagement between the rotary thread rolling tools and the work piece.

As more fully explained in prior Bedker U.S. Pat. No. 2,701,484, gears are provided which interconnect the two thread rolling tools. In operation, the fixture is arranged so that one of the tools contacts the rotating work piece in advance of the other, and is driven in rotation thereby. Rotation of this thread roll through a series of five gears, two of which rotate on the axes of the thread rolls, drives the other thread roll in precisely timed relation until it also solidly engages the rotating work piece. At this time the two thread rolls are in exactly timed relation. As the fixture is advanced to cause the thread rolls to assume a position close to diametrically opposed zones on the rotating work piece, a lost motion connection permits the differential rotation required between the thread rolls as a result of their generally tangential advance.

The provision for lost motion comprises drive means associated with the gear which is mounted in coaxial relationship with the thread roll. This drive means comprises a key extending radially across one side of the gear and the hub 10 is provided with a relatively wide radially extending drive slot 18 to receive the driving key, the location of which is indicated in dotted lines at 20 in FIG. 3.

The hub 10 is provided at one end with a radially extending abutment flange 22 the side of which adjacent the thread roll or sleeve 12 is inclined as indicated at 24.

In order to retain the thread roll 12 on the hub 10 against axial displacement, the hub is provided with a plurality of annular grooves 26. The grooves are of V-shaped cross-section and conveniently, the sides of the grooves may be inclined at angle of 45° with respect to the axis of the hub. The rings receive a resilient snap

ring 14 which as best seen in FIG. 3 is of square cross-section so that the two radially inner surfaces thereof interfit with the inclined surfaces of one of the grooves 26. The radially outer surfaces of the ring 14 are shaped so that either may conform to an inclined or beveled surface 28 formed on the thread roll or sleeve 12 directly adjacent the opening 30 therethrough.

Preferably, the thread roll or sleeve 12 is provided with beveled or inclined surfaces 28 at both sides thereof so that the roll or sleeve 12 may be reversed on the hub. Similarly, it is preferable that the two inclined or tapered surfaces at the radially inner side of the ring 14 shall be equally inclined so that the ring may also be reversed and so that no particular attention need be given to the orientation of the ring when it is assembled on the tool.

While the ring 14 is shown as of square cross-section, it will be appreciated that the inclination of the sides may differ, although the inclination of the two radially inner inclined sides should be the same and the inclination of the two radially outer inclined sides should be the same and should also be the same as the inclination of the taper provided on the flange 22, and roll surfaces 28.

In the thread rolling operation very substantial axial forces are developed and the employment of the snap ring having the configuration disclosed herein is particularly useful. In the first place, it provides a maximum dimension of ring in position to oppose the shearing action developed by the axial thrust on the thread roll. Secondly, the axial thrust of the thread roll, when directed to the right as seen in FIG. 3, establishes forces having inwardly acting components tending to maintain the rings firmly in their seats. Moreover, the forces developed between the thread roll and the rings are in a direction perpendicular to the opposite surface of the groove which receives the ring.

The thread roll 12 is provided on its periphery with the thread formation indicated at 32. The opening 30 through the thread roll, as best seen in FIG. 1, is made up of a cylindrical portion 34 and a flat portion 36. Similarly, the hub 10 has a cylindrical outer surface 38 which is interrupted only by the grooves 26 and by a flat surface 50 which is shaped to engage the flat surface 36 on the roll 12.

Accordingly, the thread roll is maintained in fixed relation on the hub 10 by engagement between the abutment flange 22 and the ring 14 and by engagement between the flat surfaces 36 of the thread roll and 40 of the hub.

The present construction permits manufacture of the thread forming roll or sleeve from pre-drilled commercially available stock, simply by cutting off wafers of the proper width to accommodate the length of thread required. This of course results in substantial savings in machining and material costs. The wafers are then broached to provide the flat surfaces 36 in the interior hole.

It has further been found to be entirely satisfactory to form all thread forming rolls or sleeves from stock having the same internal diameter as for example, 0.800 inch. This of course means that all hubs may be of corresponding transverse dimensions so that a very great economy in maintaining a proper stock of parts is permitted.

Since the hub is retained and re-used, it eliminates those operations that would normally have to be per-

formed on hub portions of the previously used unitary thread rolls, such as slotting, honing, boring, etc.; again resulting in substantial savings on material and machining.

Since the hub, which serves as the journal rotating on a pin in the thread rolling fixture, and the thread forming roll or sleeve which actually does the work, or separate, the material and/or heat treatment provided therefor may be controlled separately so that the hub can be made from the best material and given the best heat treat for the job it has to do. Similarly, the thread forming roll or sleeve can be made from the best material and heat treated in accordance with the requirements for the thread forming which it has to do. Thus, the composite roll is characterized in that all portion thereof have the physical characteristics best suited for the requirements thereof.

Since there are no hubs or bosses on the thread forming roll or sleeve, it is possible to double or triple the number of parts that may be mounted on grinders at one time which will afford the possibility of a major reduction in grinding time.

Since the internal diameter of the sleeve is quite large and will fit a wide variety of hubs, less tooling will be required in the manufacture, such as arbors, etc. Also, the arbors of the machines used in producing the rolls, such as the arbors of grinding machines for example, can be larger than would otherwise be the case and accordingly, can be made longer without loss of rigidity, making it possible to mount still more parts on the machine at one time for a single operation.

The thread forming roll or sleeve is interchangeable with the number of different hubs and by using the appropriate hub, the assembly may be adapted for use on a variety of different thread rolling fixtures. Accordingly, the number of parts which are kept in stock may be substantially reduced, as for example, by as much as 60-70 percent.

The retaining ring is an important part of the assembly since the axial force is a normal and necessary reaction of thread rolling and it is necessary to have a retainer that is strong and will not release or pop off during use. At the same time, it must be small because of space limitations. By using a retainer ring of square cross-section with the surfaces inclined as suggested herein at approximately 45° to the axis of the hub, a maximum thickness of the ring is provided at the shearing point and the axial force of the sleeve tends to force the retainer ring down into the groove, thus locking it in place.

Accordingly, there is not only a substantial reduction in material cost and in manufacturing cost in the production of the composite thread rolling tool of the present invention, but there is also the substantial savings which may be effected due to the fact that the thread rolls or sleeves may be fitted onto different hubs designed for different types of thread rolling fixtures. Thus, in the final analysis, a single thread roll may be adapted for any type fixture by associating it with the proper hub component.

What I claim as my invention is:

1. A thread rolling tool having a roll forming portion provided with a thread formation for rolling threads on a work piece and an apertured hub portion fixed to said roll forming portions for mounting said tool on a thread rolling fixture, said tool being in the form of a sub-assembly applicable to and removable from a tool

support as a unit, said tool consisting in its entirety of: an elongated hub having an opening therethrough to provide for mounting the tool on a tool support, an abutment at one end, an intermediate portion adjacent said abutment having an outer roll-supporting surface, and an outer configuration beyond said roll-supporting surface from said abutment cooperable with a roll-securing member to mount a thread roll sleeve on said hub, with one side thereof located against said abutment,
 a rolling forming portion in the form of a sleeve having a threaded outer surface, an opening therethrough conforming to the roll-supporting surface of said hub, and means acting between said roll-forming portion and said hub to prevent relative rotation therebetween and to provide for rotation of said hub and roll-forming as a unit,
 and a roll-securing member engaged with said outer configuration on said hub and engaged with the side of said roll-forming portion remote from the abutment on said hub to lock said roll-forming portion firmly against said abutment.

2. A tool as defined in claim 1 in which said sleeve has flat parallel end faces which permit assembly of a plurality of said sleeves in end abutment on arbors during formation of the threads thereon.

3. A tool as defined in claim 1 in which said opening through said sleeve and said intermediate exterior surface of said hub are mating cylindrically shaped internal and external surfaces including mating flat surface portions providing a driving connection therebetween.

4. A thread rolling tool having a roll forming portion provided with a thread formation for rolling threads on a work piece, and an apertured hub portion fixed to said roll forming portion for mounting said tool on a thread rolling fixture, said roll forming portion and said hub portion comprising a separate integral sleeve and

a separate integral hub, said sleeve having an opening therethrough shaped to receive a portion of said hub, removable means mounting said sleeve in fixed position on said hub, the means for mounting said sleeve in fixed position on said hub comprising an annular groove in the exterior surface of said hub, and a split ring received in said groove and constituting an abutment to prevent movement of said sleeve axially of said hub.

5. A tool as defined in claim 4 in which said groove is of V-shape in cross-section, and in which the radially inner surface of said ring is of a matching V-shape.

6. A tool as defined in claim 5 in which said ring is of substantially square cross-section with sides inclined at about 45° to the axis of said hub.

15 7. A tool as defined in claim 5 in which the radially outer side of said ring includes an inclined surface adjacent said sleeve which is straight in transverse section, and in which the surface of said sleeve adjacent the opening therethrough is inclined to interfit with the inclined surface on said ring.

8. A tool as defined in claim 5 in which said hub has an integral annular abutment at one end engageable with the adjacent side of said sleeve.

25 9. A tool as defined in claim 8 in which the surface of said abutment is inclined at the same angle as the said inclined surface at the radially outer portion of said ring to provide for reversibility of said sleeve.

10. A tool as defined in claim 8 in which the surface of said abutment is inclined at the same angle as the said inclined surface at the radially outer portion of said ring, and in which the radially outer surface of said ring has the portion thereof remote from said sleeve inclined at the same angle as the angle of inclination of the surface engageable with said sleeve to provide for reversibility of said sleeve and said ring on said hub.
